UNITED STATES PATENT OFFICE.

THOMAS KELLY, OF BUTTE, MONTANA.

LEGGING.

Application filed August 4, 1926. Serial No. 127,127.

This invention appertains to apparel and more particularly to a covering form for the calf of the leg.

One of the salient features of the present invention is the provision of a legging form adapted to be worn under the stocking and so formed as to give a full shape to the calf of the leg, and an object of the invention is the provision of a celluloid form for engaging the calf of the leg just below the knee and extending to the ankle, the shell being of a light weight and of a flesh color, whereby the same can be worn under the thinnest hosiery.

15 A further object of the invention is the provision of a thin shell like form split longitudinally for snapping over the calf of a leg, the form being provided with delicate split steel rings for normally maintaining 20 the shell of the form in a closed position about the leg.

25 A further object of the invention is the provision of pads preferably formed of sponge rubber carried by the inner face of the shell for engaging the leg of the wearer whereby the device will be exceedingly comfortable to wear.

30 A further object of the invention is to provide a leg form attachment for women's wear which can be worn next to the skin and under the stocking, which will not only give an attractive shape to the leg, but which will also be a protection against the weather and constitute means for concealing varicose 35 veins, and the like.

40 A further object of the invention is to provide a device of the above character, which will be durable and efficient in use, one that will be simple and easy to manufacture and which can be placed upon the market at a reasonable cost.

45 With these and other objects in view, the invention consists in the novel construction, arrangement and formation of parts, as will be hereinafter more fully described, claimed, and illustrated in the accompanying drawings, in which drawings:

Figure 1 is a perspective view of the improved device showing the same in use,

50 Figure 2 is a perspective view of the device showing the same in its partly open position ready to be placed about the leg of a person,

55 Figure 3 is a detail horizontal section taken through the device showing one of the

resilient rings normally maintaining the devices in closed position about the leg,

Figure 4 is a similar section illustrating one of the pads for engaging the leg, and

Figure 5 is a fragmentary vertical section 60 through the device illustrating the formation of the shell thereof and the arrangement of the pads and the resilient rings therein.

Referring to the drawings in detail, wherein similar reference characters designate corresponding parts throughout the several views the letter A generally indicates the improved device, which comprises a shell 10, formed of a resilient light material, such as celluloid or the like. Inasmuch as the 70 shell is of celluloid, it will possess considerable resiliency and be adapted to retain its shape, and furthermore inasmuch as molded celluloid is smooth, there will be no liability of the stocking frictionally adhering to the 75 surface of the shell to cause puckering or other disarrangement of the stocking which might occur if the shell were of a material presenting a rough surface, such for example as a cloth material. This shell 10 is 80 molded so as to give the appearance of a full shaped leg and the shell is split longitudinally as at 11 from one end thereof to the other. This slit portion can be either at the front or back of the shell. The material is 85 preferably of a flesh color so that if the same is seen through a stocking, the shell will give the appearance of natural skin.

As shown this shell is adapted to be placed on the calf of the leg just below the knee 90 and is adapted to extend down to and about the ankle. Thus the shell itself engages the leg of the wearer at the knee and ankle.

In order to maintain the shell in a closed position about the leg and the side edges of 95 the split 11 in contact with one another, the inner face of the shell can be provided at spaced points with delicate spring steel split rings 12, extending about the inner side of the shell, and the ends of these rings are 100 placed in registration with the split of the shell as clearly shown in Figure 3 of the drawings.

In order to add to the comfort of the person wearing the device, the inner surface of 105 the shell is also preferably provided with annular pads 13 which can be formed from sponge rubber. The pads are also slit at the slit of the shell as shown in Figure 4 of the drawings. It will be observed by reference 110

to Figures 3, 4 and 5 of the drawings that the pads 13 are of greater cross sectional dimensions than the resilient rings 12 so that the pads will project inwardly a greater distance than the rings and consequently the rings will be prevented from coming in contact with the skin.

If desired the shell itself can be provided throughout its entire area or at certain defined points with minute ventilating openings 14.

In applying the device to the leg, it is merely necessary to spring the shell open at the slit front thereof and place the same about the leg and after the release of the shell, the same will spring to closed position and naturally adapt itself to the leg.

The device will be found to be light in weight, easy to wear and practically unnoticeable and is especially adapted for protection against the cold in the winter.

Changes in details may be made without departing from the spirit or scope of this invention, but:

25. What I claim as new is:

1. A legging form adapted to be worn under a stocking and comprising a shell shaped to conform to a full formed leg, the shell being slit longitudinally and adapted 30 to engage the leg adjacent to the ankle, a

plurality of resilient split rings secured to the inner face of the shell, and a plurality of split annular pads of sponge rubber secured to the inner face of the shell and of greater cross sectional dimension than the 35 resilient rings.

2. A legging form adapted to be worn under a stocking and comprising a thin, longitudinally split shell shaped to simulate a full formed calf, resilient means for maintaining the shell closed, and cushioning pads of relatively soft material extending transversely about the inner side of the shell at different elevations.

3. A legging form adapted to be worn 45 under a stocking and comprising a thin shell slit longitudinally and shaped at its upper and lower ends to respectively conform to and snugly contact with the calf of the leg below the knee and above the ankle, a plurality of resilient rings upon the inner side 50 of the shell at different elevations between the said upper and lower end portions thereof, and pads likewise secured to the inner side of the shell at different elevations and 55 alternating with the said rings and extending about the inner side of the shell.

In testimony whereof I affix my signature.

THOMAS KELLY.
